Patented Apr. 9, 1918.

Inventor:

Frank J. Kristofek,
by: Howard Fischel,
Attorney.

UNITED STATES PATENT OFFICE.

FRANK J. KRISTOFER, OF ST. PAUL, MINNESOTA, ASSIGNOR TO BROWN & BIGELOW, OF ST. PAUL, MINNESOTA, A CORPORATION OF MINNESOTA.

TOP.

1,262,061.

Specification of Letters Patent.

Patented Apr. 9, 1918.

Application filed June 27, 1917. Serial No. 177,371.

To all whom it may concern:

Be it known that I, FRANK J. KRISTOFER, a citizen of the United States, residing at St. Paul, in the county of Ramsey and State of Minnesota, have invented a new and useful Improvement in Tops, of which the following is a specification.

My invention relates to spinning tops and the primary object is in providing a device which is of simple construction and inexpensive to manufacture.

A further object is in providing a spinning top with a center peg which is of material soft enough to be abraded by ordinary stamping burs.

It is also an object to provide burs on the body and other portions of the top which will abrade the axial peg of the same when the portions of the top are assembled so as to hold them rigidly to the peg without additional operation.

It is an object to have a top with a flat thin circular body portion and a separate support which is adapted to give a long bearing surface on the peg on the top so as to prevent the peg from becoming loose or moving transversely under ordinary use.

A further object is in providing a top with a non-metallic upper surface which can be used for a display surface or any other desired object.

In the drawing forming part of this invention:

Figure 1 is a perspective of the top.
Fig. 2 is a plan view of the top.
Fig. 3 is a central cross section of Fig. 2 taken on the line 3—3.
Fig. 4 is a side elevation of the top.
Fig. 5 is a cross section of a portion of the top taken on the line 5—5 of Fig. 3.

Fig. 6 is a side elevation partly in section of an alternative construction of the top.

In the drawing, A represents a top having a center or axial cylindrical peg 1 which is formed out of wood or any other suitable material. The lower end of the peg 1 is pointed so as to form a pointed surface 2 which rests on the surface on which the top is spun, thereby making a small frictional contact.

The top A is formed with a circular body portion 3 which is formed out of thin sheet material and has a central depending flange 4 formed when a hole 16 is made in the body portion and having ragged peg engaging

burs 5 on its lower edge. The outer circumference of the body portion 3 is turned inward so as to form a circumferential engaging flange 6 which is adapted to engage the surface of the disk 7 to hold it securely against the upper surface 8 of the body portion 3.

A hollow cup shaped support or brace 9 having an upwardly projecting central flange 10 which is formed when a central opening 17 is formed in the support and having ragged peg engaging burs 11 formed on the upper edge thereof is adapted to brace the peg 1. The support 9 is formed with a lower horizontal edge 12 which impinges against the upper surface of the disk 7 when the support 9 is in place on the peg 1, to hold the inner portion of the disk 7 securely against the surface 8 of the body portion 3. By forming the support 9 hollow and of thin material, no central weight is added to the top and the distance between the bearing points of the flanges 4 and 10 is of sufficient length to give a substantial bearing or brace for the peg 1.

It is preferred to have the peg 1 of a soft nature such as wood or other suitable material so that it will be easily abraded by the burs 5 and 11.

When the top A is assembled, the burs 5 are adapted to abrade the peg 1 forming grooves 13 longitudinally of the peg and the burs 11 formed on the support 9 are adapted to abrade the peg 1 of the top longitudinally forming similar grooves 13, thus the burs 5 and 11 hold the body 3 and the brace or support 9 rigidly to the peg 1 and the surface 12 of the support 9 impinges sufficiently against the disk 7 to rigidly brace the peg 1 against transverse movement in relation to the body 3 and the support 9.

The body portion 3 is positioned closer to the pointed end of the peg 1 than to the top or engaging end of the peg 14, so that when it is desired to spin the top, the portion 14 is engaged between the fingers and given a quick twist. The circular portion giving sufficient momentum to spin the top for a considerable length of time.

The circumferential flange 6 tends to increase the weight around the circumference of the body portion 3, thus assisting the momentum of the top. The top A is so formed as to perfectly balance itself when spinning and the disk portion 7 which is preferably

of a non-metallic material gives an upper surface 15 on which any suitable display matter can be illustrated. It is obvious that the burs 5 and 11 can be bent inward after the body portion 3 and the support 9 have been forced in place on the peg 1, to insure rigidly holding the peg 1 to the body portion of the top. The top is of simple construction, easily assembled and inexpensive to manufacture.

In the construction illustrated in Fig. 6, the body portion 3 of the top A, is formed of cardboard or a non-metallic substance and is held to the peg 1 by means of two supports 9 which are forced on to the peg 1. The supports or braces 9 are of the same construction as illustrated in Fig. 3 and are adapted to impinge against either side of the surface of the body 3 so as to hold the body portion 3 rigidly in relation to the peg 1. Washers 18 are secured in any suitable manner to the outer edge 19 of the non-metallic body 3 and are adapted to protect the edge of the same and also increasing the weight around the circumference of the body 3 so as to increase the momentum of the top when spinning.

By forming the top with a non-metallic body portion 3, very little metal is used in the construction of the same and the hollow supports 9 sufficiently hold and brace the peg and body portion so as to give a good substantial construction. If it is desired, the supports can be rigidly secured to the body portion 3 in any suitable manner.

I have illustrated a particular construction in the drawings, but I desire to have it understood that I do not wish to confine myself to this particular construction, but that the invention can be carried out by other means and applied to other uses within the scope of the following claims.

I claim—

1. In a top having a thin flat body portion, a peg passing axially through said body portion, burs formed on said body portion for engaging said peg, a supporting

element adapted to rest on said body portion and burs formed on said supporting element for engaging said peg to hold the same at right angles to said body portion.

2. In a device of the class described, a spinning top having a flat thin circular body portion, a circular disk secured to said body portion by a circumferential flange, said flange being integral with said body portion, a peg passing through said body portion axially, burs formed on said body portion for rigidly engaging said peg, a cup shaped support having peg engaging burs formed integral therewith and a flange formed on said support adapted to impinge against said circular disk to brace said peg against transverse movement.

3. In a top, having a center peg with a pointed lower end, a flat thin body portion, a hollow support for bracing said peg against transverse movement in relation to said body and means on said body and support for longitudinally grooving the surface of said peg to rigidly fix said support and body to said peg.

4. In a spinning top, having a center cylindrical peg with a pointed lower end, a body portion formed of thin sheet metal, peg engaging burs formed on said body portion, a non-metallic disk, a circumferential flange formed on said body portion to hold said disk to the surface of said body portion and a hollow brace secured to said peg adapted to impinge against the surface of said disk to hold the inner portion of said disk against said body portion and to brace said peg against transverse movement.

5. In a spinning top, having a non-metallic axial peg, a circular flat thin body portion having means for longitudinally abrading said peg to rigidly hold said body portion thereto and a cup shaped brace having means for abrading the surface of said peg and engaging means to impinge against said body portion to brace said peg against transverse movement.

FRANK J. KRISTOFEK.
